(57) CLAIM

The ornamental design for a plunge bra for women with limited mobility as shown and described.

DESCRIPTION

FIG. 1 is a front perspective view of a plunge bra for women with limited mobility showing our new design; FIG. 2 is another front perspective view thereof; FIG. 3 is a front view thereof; FIG. 4 is a rear view thereof; FIG. 5 is a side view thereof; and, FIG. 6 is a side view opposite that of FIG. 5.

The shorter dashed broken lines show portions of the plunge bra which form no part of the claimed design. The longer dashed broken lines show environment which forms no part of the claimed design. The dash-dot broken lines show the boundary of the claim and form no part of the claimed design.

1 Claim, 6 Drawing Sheets
